UNITED STATES PATENT OFFICE.

ELBRIDGE G. ROBERTS, OF REDBANK, NEW JERSEY.

STEAM-GENERATOR.

SPECIFICATION forming part of Letters Patent No. 752,301, dated February 16, 1904.

Application filed June 22, 1903. Serial No. 162,473. (No model.)

To all whom it may concern:

Be it known that I, ELBRIDGE G. ROBERTS, a citizen of the United States, and a resident of Redbank, in the county of Monmouth and State 5 of New Jersey, have invented certain new and useful Improvements in Steam-Generators, of which the following is a specification.

This invention relates to improvements in the construction of water-tube steam-generators.

In order that others may understand the invention, I will first proceed to describe a structure embodying the improved features of construction and subsequently will point out in 15 the claims its novel characteristics.

In the accompanying drawings, forming a part of this specification, Figure 1 represents a side and Fig. 2 an end elevation of a generator which includes my invention.

20 In the respective figures like numerals of reference indicate corresponding parts.

The principal parts of the structure shown comprise the main vertical side distributing-pipes 1, which communicate with a cross-pipe 25 connected to the elevated steam and water drum 2 and also communicate with the horizontal bottom distributing-pipes 3, which form the base of the structure. This organization or design of the parts enumerated is common 30 to the type of generator shown.

The structure which includes the present invention consists in the addition of a horizontal transverse distributing-pipe 4, which communicates with the vertical side distributors 35 1 near the top of the space 5 reserved for the furnace-chamber and also with a series of single pipe-loops 6, arranged longitudinally of the chamber, each leading by means of a connected series of pipes 7 to a water-drum 8, located below the steam and water drum 2 and the normal water-level.

At the rear end of the furnace-chamber space 5 a series of vertical pipes 9, denominated "risers," are connected with the rear transverse base distributing-pipe and form the end 45 wall of the furnace-chamber. This series of risers 9 are each connected with a series of single pipe-loops 10, which also extend longitudinally of the furnace beneath the loops 6, and the loops connect with a series of pipes 50

11, leading to the water-drum 8. A series of similar risers 12 are connected with the longitudinal base distributing-pipes and form the side walls of the furnace-chamber. This series of risers 12 are also each connected with 55 a double series of single pipe-loops 13, arranged transversely one above the other and both above the longitudinally-arranged loops 6 and each communicating with the elevated steam and water drum 2 by means of the series of connected pipes 14.

The essence of the present invention consists in the use of a series of single pipe-loops between the distributors and the series of risers and the water or water and steam drum. 65

The invention also embraces the use of a distributing-pipe 4 across the front of the furnace and a communicating water-drum 8, located below the normal water-level of the generator, and, further, in the novel setting of the 70 loops, each being rendered easy of access or removal from the front of the generator without disturbing the one adjacent.

In the close arrangement of the risers and loops it will be observed that the space occupied is reduced to a minimum, the separation of the same being equal only to the projection of the flange on the connections which contact with an adjacent one. In the use of these single loops as described each loop receives comparatively cold water from the bottom distributors and is subjected directly to the hottest gases of combustion. The great advantage in this is that the greater contrast there is between the temperature of the inside and 75 the outside of the tube the greater the efficiency of the boiler, inasmuch as heat units will pass through metals in accordance with the square of the difference of the temperature between the interior and exterior of the same. 85

The advantageous point therefore obtained by the use of a single loop between the risers and the drums, as shown, is that a greater evaporation can be obtained from the same number of square feet of heating-surface, and 90 at the same time a lower stack temperature is obtained, due to the absorption of the heat of the gases of combustion by the distribution of the water of low temperature through a series of single loops only instead of through a 100

number or stack of loops communicating with each riser, as in former structures of this type.

By the use of the water-drum below the line of water-level a large body of water is carried, which prevents rapid fluctuations of the water-level frequently experienced in water-tube generators. Other advantages are also secured incidental to the present improvements wherein the use of fire-brick in the furnace-walls is eliminated and the accessibility to and removal of all or any of the pipes that form the structure is rendered convenient, the vertical risers at the several connections being made with right and left standard pipe-threads.

Having thus fully described my invention, what I claim, and desire to secure by Letters Patent, is—

1. The combination in a water-tube steam-generator of base distributing-pipes, a water-drum centrally located below the normal water-level and a series of intermediate communicating pipe-loops composed of a single return-bend and arranged above the furnace-chamber, as set forth.

2. In a water-tube generator a fire-box having an end wall and side walls formed of closely-set vertical water-tubes supplied from horizontal base distributing-pipes, each vertical tube being combined with a single pipe-loop arranged in two series across and above the furnace-chamber; a water-drum located below the normal water-level communicating with one series of said single loops, and an elevated steam and water drum communicating with the other series of said single loops, as shown and described.

3. The combination, in a water-tube steam-generator of a transverse distributing-pipe located at the front of the furnace; a water-drum located below the normal water-level, and a

series of intermediate communicating pipe-loops composed of a single return-bend and located above the furnace-chamber, as set forth.

4. A water-tube steam-generator, comprising the following elements; horizontal base distributing-pipes 3; vertical side distributing-pipes 1 communicating therewith and with an elevated steam and water drum 2; a transverse distributing-pipe 4 communicating with the vertical side distributing-pipes 1 and located above and at the front of the furnace-chamber 5; a series of vertical circulating-pipes 12 rising from the longitudinal base distributing-pipes 3; a double series of single pipe-loops 13, connected with said risers 12 and arranged horizontally and transversely in the path of the rising furnace-gases, and communicating with the elevated steam and water drum 2; a series of vertical circulating-pipes 9 rising from the rear transverse base distributing-pipe; a series of single pipe-loops 10 connected with said risers and arranged horizontally and longitudinally directly above the furnace-chamber and communicating with a water-drum 8 located below the water-level of the generator, and a series of single pipe-loops 6 rising from the transverse distributing-pipe 4, and arranged in line with and above the series of such pipe-loops 10 in the furnace-chamber which also communicate with said water-drum.

Signed at New York, in the county of New York and State of New York, this 20th day of June, A. D. 1903.

ELBRIDGE G. ROBERTS.
